DENNIS H. TURNER, OF SEMINOLE, OKLAHOMA

BURNER

Application filed October 27, 1928. Serial No. 315,474.

This invention relates to a burner adapted to be employed for consuming gas and oil direct from oil wells.

An object of the invention is the provision 5 of a burner for consuming gas or gas saturated with oils from the oil well in which the pressure of the gas is not sufficient to provide for an efficient flame.

A further object of the invention is the 10 provision of a burner in the form of an elongated casing divided into a gas chamber and a mixing chamber and in which a plurality of fans are driven by means of steam jets for drawing in and mixing with the gas the 15 proper quantity of air.

This invention will be best understood 20 from a consideration of the following detailed description, in view of the accompanying drawings forming a part of the specification; nevertheless it is to be understood that the invention is not confined to the disclosure, being susceptible of such changes 25 and modifications which shall define no material departure from the salient features of the invention as expressed in the appended claims.

In the drawings:

Figure 1 is a longitudinal view of a burner 30 constructed in accordance with the principles of my invention,

Figure 2 is a horizontal section of the same,

Figure 3 is a fragmentary enlarged vertical section of the gas chamber,

Figure 4 is a longitudinal vertical section 35 of the burner,

Figure 5 is a fragmentary plan view showing the fans for forcing in air,

Figure 6 is an end view of the burner,

Figure 7 is a horizontal section taken along the line 7-7 of Figure 6.

Referring more particularly to the drawings, 10 designates a gas chamber formed of two sections of tubing 11 and 12 connected together by an internally threaded sleeve 13. One end of the tube 11, as shown at 14, is reduced and receives a connection 15 in communication with the pipe 16 which supplies gas to the chamber 10. The inner end of the tubing 11 is closed by a plate 17 having per-

forations or passages 18. The inner end of the tubing 12 is threaded into a boss 19 connected with a housing 20.

A sleeve 21 is slidably mounted on a tube 22 which projects through the spider and has an expanded and cup-shaped end 23. The other end of the tube 22 projects through a central passage in the plate 17, and is connected with a head 24 located within the housing 20.

The sleeve 21 has rigidly secured thereto a valve 25 having passages 26 adapted to be aligned with the passages 18 in the plate 17. A coil spring 27 embraces the sleeve and is connected at one end to pins 28 and at the other end to the valve 25 for maintaining said valve away from the plate 17. The sleeve is provided with slots 29 which receive the ends of the pins 28 for guiding the sleeve in its reciprocating movement on the tube 22. The pins are secured in the tube 22.

A steam pipe 30 is connected with a source of steam and has one end projecting into the tube 22. The head 24 is provided with nozzles 31 which are located within the housing 20 for a purpose which will be presently explained.

The housing is divided into three sections, a central section 31^a and two laterally projecting sections 32 and 33. A fan 34 is located within the central section 31^a while fans 35 and 36 are respectively located in the laterally projecting portions 32 and 33. It will be noted that the inner ends of the vanes of the fan all project within the central portion of the housing, each disposed adjacent the end of a nozzle 31 and also adjacent the inner end of pipes 37 which are in communication with the passages 18. It will thus be seen that there are three nozzles 31 and also three of the pipes 37 with a pair of each of the nozzles 31 and pipes 37 being located adjacent the vanes of the fan so that when the steam and gas are impinged upon the vanes or blades of the fans said fans will be revolved for drawing in air through the open ends 38 of the laterally disposed sections 32 and 33 of the housing 20 and also through the opening 39 at the upper end of the section 31^a.

A frustoconically-shaped pipe 40 is in open

communication with the housing 20 and its outer free end 40^a forms a discharge or nozzle for the combustible mixture formed in the housing 20.

- 5 Located upon the top of the free end of the pipe 40 is a pair of nozzles 41 and 42 respectively connected with pipes 43 and 44. The pipe 43 supplies oil to the nozzle 41 while the pipe 44 supplies steam to the nozzle 42, and these two elements are combined and are drawn into the flame by the suction created by the combustible materials passing through the outlet 40^a of the tube 40.

10 The nozzle 41, as shown more particularly in Figure 7, has its inner end reduced, as shown at 45, and plates 46 and 47 are located within the nozzle and are tapered from their outer to their inner ends, providing a plurality of channels 48, 49 and 50, all located 20 in a horizontal row. The nozzle 42 is similarly constructed to the nozzle 41.

15 The operation of my device is as follows: Steam is supplied to the pipe 30 while gas is supplied by the pipe 16 and the gas enters 25 the chamber 10 and also the cup 23 so that gas passes through the tubular member 22 and into the head 24 with the steam from the pipe 30. The gas also passes around the valve 25 and through the passages 18 to the 30 tube 37 whence it impinges upon the blades of the fans or when sufficient pressure is lacking in the gas to cause rotation of the fans, steam from the pipe 30 will act on the blades of the fans and cause them to revolve 35 at great speed. The suction created by the fans will draw in air which will be thoroughly mixed with the gas and steam in the housing 20 and which mixture is forced through the tube 40 through the outlet 40^a, where it is 40 ignited.

45 A certain amount of oil normally passes through the pipe 16 with the gas, and this is burned at the end of the nozzle 40^a. Since the gas is at a high pressure the oil is readily consumed. Before the gas is received by lead pipe 16 it passes through the usual trap (not shown) where excessive oil is collected from the gas. This oil which is collected in the trap may be collected in the 50 storage chamber and then conducted to pipe 43. However pipe 43 is connected with a suitable source of supply of oil and this oil is forced through the nozzle 41 and into the burned gas exuding from the nozzle 40^a. By 55 this construction it is unnecessary to cut off the gas burner until all the oil from the line has been removed.

I claim:

- 60 1. A burner comprising a casing, a partition dividing the casing into a gas chamber and a mixing chamber, said partition having a plurality of restricted passages for placing the compartments into communication with each other, fans mounted in the mixing chamber, a pipe in communication with a source of

steam and provided with nozzles adapted to impinge steam against the fans for causing rotation of the fans, the mixing chamber adjacent the fans being open to the atmosphere whereby said fans will draw in air and mix it with the gas from the gas chamber, the gas chamber being in communication with a source of gas.

2. A burner comprising a casing, a partition dividing the casing into a gas chamber and a mixing chamber, said partition having a plurality of restricted passages for placing the compartments into communication with each other, fans mounted in the mixing chamber, a pipe in communication with a source of steam and provided with nozzles adapted to impinge steam against the fans for causing rotation of the fans, the mixing chamber adjacent the fans being open to the atmosphere whereby said fans will draw in air and mix it with the gas from the gas chamber, the gas chamber being in communication with a source of gas, said pipe being in communication with the gas chamber so that a predetermined quantity of gas is supplied with the steam to the mixing chamber.

3. A burner comprising a casing, a partition dividing the casing into a gas chamber and a mixing chamber, said partition having a plurality of restricted passages for placing the compartments into communication with each other, fans mounted in the mixing chamber, a pipe in communication with a source of steam and provided with nozzles adapted to impinge steam against the fans for causing rotation of the fans, the mixing chamber adjacent the fans being open to the atmosphere whereby said fans will draw in air and mix it with the gas from the gas chamber, the gas chamber being in communication with a source of gas, and a pipe for supplying steam to and located within the first-mentioned pipe.

4. A burner comprising a casing, a partition dividing the casing into a gas chamber and a mixing chamber, said partition having a plurality of restricted passages for placing the compartments into communication with each other, fans mounted in the mixing chamber, a pipe in communication with a source of steam and provided with nozzles adapted to impinge steam against the fans for causing rotation of the fans, the mixing chamber adjacent the fans being open to the atmosphere whereby said fans will draw in air and mix it with the gas from the gas chamber, the gas chamber being in communication with a source of gas, and a pipe for supplying steam to and located within the first-mentioned pipe, the second-mentioned pipe terminating short of the nozzles.

5. A burner comprising a casing, a partition dividing the casing into a gas chamber and a mixing chamber, said partition having a plurality of restricted passages for placing the compartments into communication with

each other, fans mounted in the mixing chamber, a pipe having a header located in the mixing chamber provided with a plurality of nozzles located adjacent the fans, a steam pipe projecting into the first-mentioned pipe for supplying to the nozzles steam which is impinged against the fans, the mixing chamber adjacent the fans being open to the atmosphere whereby said fans will draw in air and mix it with the gas from the gas chamber, the gas chamber being in communication with a source of gas.

6. A burner comprising a casing, a partition dividing the casing into a gas chamber and a mixing chamber, said partition having a plurality of restricted passages for placing the compartments into communication with each other, fans mounted in the mixing chamber, a pipe having a header located in the mixing chamber provided with a plurality of nozzles located adjacent the fans, a steam pipe projecting into the first-mentioned pipe for supplying to the nozzles steam which is impinged against the fans, the mixing chamber adjacent the fans being open to the atmosphere whereby said fans will draw in air and mix it with the gas from the gas chamber, the gas chamber being in communication with a source of gas, the end of the steam supply pipe terminating short of the header.

7. A burner comprising a casing, a partition dividing the casing into a gas chamber and a mixing chamber, said partition having a plurality of restricted passages for placing the compartments into communication with each other, fans mounted in the mixing chamber, a pipe having a header located in the mixing chamber provided with a plurality of nozzles located adjacent the fans, a steam pipe projecting into the first-mentioned pipe for supplying to the nozzles steam which is impinged against the fans, the mixing chamber adjacent the fans being open to the atmosphere whereby said fans will draw in air and mix it with the gas from the gas chamber, the gas chamber being in communication with a source of gas, the first-mentioned pipe being in communication with the gas chamber.

8. A burner comprising a casing, a partition dividing the casing into a gas chamber and a mixing chamber, said partition having a plurality of restricted passages for placing the compartments into communication with each other, fans mounted in the mixing chamber, a pipe in communication with a source of steam and provided with nozzles adapted to impinge steam against the fans for causing rotation of the fans, the mixing chamber adjacent the fans being open to the atmosphere whereby said fans will draw in air and mix it with the gas from the gas chamber, the gas chamber being in commun-

cation with a source of gas, the end of the mixing chamber being tapered to provide a burner nozzle.

9. A burner comprising a casing, a partition dividing the casing into a gas chamber and a mixing chamber, said partition having a plurality of restricted passages for placing the compartments into communication with each other, fans mounted in the mixing chamber, a pipe in communication with a source of steam and provided with nozzles adapted to impinge steam against the fans for causing rotation of the fans, the mixing chamber adjacent the fans being open to the atmosphere whereby said fans will draw in air and mix it with the gas from the gas chamber, the gas chamber being in communication with a source of gas, the end of the mixing chamber being tapered to provide a burner nozzle, the burner being provided with a pair of auxiliary nozzles, one of the last mentioned nozzles adapted to be placed in communication with a source of oil and the other being connected with the source of steam.

10. A burner comprising a casing, a partition dividing the casing into a gas chamber and a mixing chamber, said partition having a plurality of restricted passages for placing the compartments into communication with each other, fans mounted in the mixing chamber, a pipe in communication with a source of steam and provided with nozzles adapted to impinge steam against the fans for causing rotation of the fans, the mixing chamber adjacent the fans being open to the atmosphere whereby said fans will draw in air and mix it with the gas from the gas chamber, the gas chamber being in communication with the source of gas, the end of the mixing chamber being tapered to provide a burner nozzle, and means for supplying steam and oil to the burner.
